DAVID S. SEAMAN, OF PROVIDENCE, RHODE ISLAND.

PROCESS OR METHOD AND APPARATUS FOR SPINNING OR TWISTING AND WINDING YARN.

Application filed December 4, 1924. Serial No. 753,831.

To all whom it may concern:

Be it known that I, DAVID S. SEAMAN, a citizen of the United States, residing at Providence, in the county of Providence and State of Rhode Island, have invented an Improvement in Processes or Methods and Apparatus for Spinning or Twisting and Winding Yarn, of which the following description, in connection with the accompanying drawings, is a specification, like characters on the drawings representing like parts.

This invention relates to a process or method and apparatus for spinning and winding yarn in a continuous length upon a single receiver.

In accordance with the present invention, the yarn is spun or twisted and wound upon a series of bobbins with the trailing end of each yarn projecting from the base portion of the bobbin, whereupon the bobbins are ready for the steps that consist of transferring the full bobbin to a carrier, tying the trailing end of the yarn on one bobbin 25 to the leading end of the yarn on an adjacent bobbin, transferring the carrier to winding position, and then winding the yarn upon a single receiver in one continuous length in succession from the bobbins on the carrier. Such carrier, in the broad aspect of the invention, may be a warp beam or other desired form of yarn holding spool.

One important feature of the invention consists in a carrier provided with a series of bobbin supporting spindles which may be detachably supported to receive the full bobbins from the spinning or twisting machine, whereby the full bobbins in their relatively supported position may be transferred as a whole to winding position, and the yarn from the series of bobbins on the carrier may then be wound in a continuous length, first from one and then from another of the bobbins in a series upon the carrier to the receiver.

Another important feature of the invention consists of a flexible carrier which may be supported in straight position with the bobbin holding spindles in alinement, and thereafter, with the full bobbin thereon, may be transferred to a winding machine having a support whereby the end portions of the bobbins may be directed to a common point, so that when the yarn from a

series of bobbins has had the trailing end of one connected to the leading end of another, a continuous thread may be drawn from the entire series of bobbins in a single length and wound upon the receiving spool or other beam.

The present invention is shown as associated with machines for forming and manipulating worsted yarn, but the invention is not necessarily limited to machines of this type.

The novel features of the present invention, both as to the process or method and the apparatus for carrying the invention into effect may best be understood from the following description and the accompanying drawings of one good form of apparatus for this purpose.

In the drawings:

Fig. 1 is a perspective view of a worsted spinning machine equipped for carrying out the present invention;

Fig. 2 is an enlarged side elevation, showing more particularly the means for supporting the flexible bobbin holding grip in its bobbin receiving position on the spinning frame;

Fig. 3 is an enlarged side sectional elevation of a flexible strip showing one of the bobbin holding spindles secured thereto by spot welding;

Fig. 4 is a side elevation of one of the flexible bobbin holding strips carrying full bobbins, with the trailing end of the yarn on one bobbin secured to the leading end of the yarn on an adjacent bobbin;

Fig. 5 is a plan view of a portion of a flexible strip, showing the preferred manner of securing the bobbin holding spindles to the flexible strip; and

Fig. 6 is a perspective view of a winding machine having a support for holding the flexible strips in position with the ends of the spindles and bobbins directed toward winding position, so that the yarn may be drawn from the ends of the bobbins in succession in a continuous length and wound upon a receiver.

The spinning machine shown in Fig. 1 comprises the usual frame 1 having a cross-bar 2 on which rovings or slivers may be supported. As shown, the rovings or slivers 3 are carried by spools 4, mounted upon the bar 2, and from which the roving or

sliver may be withdrawn during the spinning operation. Extending downwardly from the bar 2 are the supports 5 carrying the usual drawing rolls 6 and 7 between which the slivers or rovings pass after being guided thereto by the guide 8. Immediately below the drawing rolls 6 and 7 is another pair of drawing rolls 9, 10 and beyond the drawing rolls 9, 10 is still another pair of drawing rolls 11 and 12, by which the roving or sliver is finally delivered to the final drawing rolls 13 and 14. The series of drawing rolls may be driven to properly deliver the roving or sliver to spinning position.

Mounted upon the spinning rail 15 are a series of spindles, as usual, which may be driven by belt connections 16 with any suitable source of power, and between the spinning spindles and the drawing rolls 13, 14 is the guide-board 17 having eyes 18 through which the yarn passes from the final drawing rolls 13, 14 to spinning position.

The machine shown in Fig. 1 is of the cap spinning type, more especially adapted for spinning fluffy yarn, such as worsted and the like, although, of course, any of the usual forms of spinning devices may be employed.

Mounted upon the rock shaft 19 supported by an arm 20 carried by the cross-supporting bar 21 is a rail supporting arm 22. Of course the number of pivotally mounted supporting arms 22 may be varied in accordance with the size of the machine, and on the ends of the arms 22 there is rigidly secured a supporting bar 23 provided at intervals with clips 24 to receive between them and the bar 23, the flexible metal strip 25 carrying a series of bobbin supports 26, the construction being such that the flexible strip 25 with the bobbin supports 26 secured thereto may be detachably supported upon the rail or bar 23 to receive full bobbins on which the yarn has been spun and wound.

When the full bobbins have been doffed or removed from the spinning spindles, they are transferred from such spinning spindles to the spindle supports 26 carried by the strips 25 and a trailing end of the yarn on one of the full bobbins is connected to the leading end from an adjacent bobbin, as indicated in Fig. 4. In order that the trailing end of the yarn on each bobbin, as the yarn is spun and wound thereon, may be available for connection with the leading end of the yarn on the adjacent bobbin when the full bobbins are transferred from the spinning position to the spindle supports 26 of the flexible strip, the present invention contemplates that when the empty bobbins are placed upon the spinning spindles 27 in the spinning machine, the end of the yarn as at *a* shall be given a turn about the base portion of the bobbin and be turned out-

wardly therefrom to extend outwardly, as indicated in Fig. 1, whereupon the machine being provided with the empty bobbins on the spinning spindles 27, the operation of spinning is started, the end *a* of the yarn of 70 each bobbin still projecting outwardly from the bobbin, as indicated at *a*, Fig. 1. When the spinning operation has been completed and the bobbins have been filled with spun yarn, as indicated in Fig. 1, the full bobbins 75 are removed from the spinning spindles 27 and placed upon the spindles 26 of the flexible strip 25, and the trailing end *a* of the yarn on one bobbin is connected or tied to the leading end *b* of an adjacent bobbin, as 80 indicated in Fig. 4. This connection between the ends of the yarn is conveniently made by tying the two ends together, as indicated at *c*, Fig. 4.

When the bobbins have been filled by the 85 spinning machine, as indicated in Fig. 1, and have been placed upon the spindles 26 secured to the flexible strip 25, the flexible strip and spindles may be removed bodily from the spinning machine by disengagement 90 from the clips 24, and thereupon the trailing ends of the yarn on the adjacent bobbins may be tied to the adjacent ends of the yarn upon other bobbins and the entire flexible strip 25 with its load or series of 95 bobbins may then be taken bodily from spinning position and transferred as a whole to winding position.

As indicated in Fig. 4, the flexible strip 25 will then support a series of filled bobbins 100 *d* in alignment with the trailing and leading ends of the yarn of the adjacent bobbins connected together. Since it is the purpose of the present invention that the yarn from the entire series of filled bobbins shall be 105 wound in a contiguous length upon a receiver and be drawn from the ends of the bobbins, it is desirable that the strip 25 on which the bobbin supports 26 are secured may be sufficiently flexible to permit bending of the strip to direct the ends of the bobbins and the spindles on which they are supported towards winding position or preferably towards a guide from which the 110 yarn may be delivered to winding position.

This circumstance is indicated in Fig. 6, wherein is shown a winding machine for winding a continuous length of yarn on to a receiver. In the machine of Fig. 6, the receiver or spool 28 is supported in bearings 29 extending upwardly from the frame 30 of the machine, and its cylindrical surface bears upon a driven roll 31 which may be rotated from any suitable source of power.

The winding machine is provided with a support 32 which is herein shown as a trough-like structure, so curved that when one of the flexible strips 25 is laid upon the support 32, the spindles and bobbins thereon 120 125 130

will have their ends directed towards winding position, so that the yarn may be withdrawn from the ends of the series of spools in succession and wound upon the receiver.

5 The support 32 is preferably provided with a strip 33 against which the end 34 of the flexible strip 25 may abut, or under which it may project when the flexible strip with its load of bobbins having the yarn 10 of the bobbins connected together, as hereinbefore described, is placed upon the support 32. If it be desired to not only wind the yarn from a series of bobbins on each metal strip continuously on to a single receiver 28, the trailing end of the yarn on one strip at the terminal thereof may be connected to the leading end of the yarn on an adjacent strip when the strips are laid upon the curved support 32, with the result 15 that any desired length of yarn in continuous lengths may be wound upon a single receiver, and in case the receiver is a warp beam, it will be apparent at once that the entire length of warp may be directly delivered from a series of spun bobbins to the warp beam itself in a continuous length.

The support 32, as shown in the present instance of the invention, may be conveniently formed as a wooden trough having a cross beam 35 supported at its outer portion by the up-rights 36 to the upper end portion 37 with which the curved surface of the support 32 may merge, in order to direct the flexible strips in curved position for winding the yarn, as in Fig. 6.

Above the series of inclined spindles and bobbins held upon the support 32 is a guide-rail 38 over which the yarn passes to a guide 39, and from this guide it is led to an upper guide-roll 40 supported by an overhead support 41 from which project arms 42. From the overhead guide 40 the yarn is then delivered in a downward direction through a traverse 43 for laying the yarn on a single receiver 28, as shown in the present instance of the invention.

The flexible strip 25 carrying spindles 26 is preferably formed of thin sheet metal with the requisite flexibility for supporting the strip and its spindles in a straight position and detachable in the spinning machine, as indicated in Fig. 1, and thereafter to readily flex in the direction of its length, as indicated in Fig. 6, so that all of the bobbins supported by the bobbin supports 26 may have their delivery ends directed towards the overhead guide or towards winding position.

60 The bobbin supports 26 may be secured to the flexible strip 25 in various ways, but a cheap and convenient way of forming such connection is to provide each of the bobbin supports 26 with a head or flange 44, spot-welding the flange 44 as at 45 to the flexible metal strip 25. By spot-welding the flange

or head 44 to the flexible strip 25 at separated points, preferably four, as indicated in Fig. 5, the various stresses to which the bobbin supports 26 are subjected will be met and counteracted by the spot-welding 70 points 45, as indicated in Fig. 5.

By the process or method and apparatus hereinbefore described, a continuous length of yarn, determined by the number of filled bobbins carried by the flexible strips, may 75 be wound directly upon a receiver from the spinning bobbins, and the yarn itself retains its elasticity, which is sometimes impaired or destroyed in spooling the yarn at high 80 speed and in starting warp spools in warping. This characteristic of the invention and its advantages may be manifested in warping the yarn direct from the spinning bobbins, or, if desired, the yarn from the spinning bobbins may be wound upon 85 smaller receivers, as indicated in the present instance, and these receivers themselves with the load of yarn thereon in continuous and desired length may be employed in the warping 90 creel.

While the invention has been herein described in connection with spinning and winding yarn in continuous length, the method or process and apparatus will work 95 equally well on two-ply or multiple-ply yarns that are twisted together on a twist frame. That is, instead of spinning the 100 yarn and placing the spun bobbins on the carrier, the advantages of the invention may be secured by twisting spun yarn into one or more ply yarn, transferring the bobbins with the twisted ply yarn onto the carrier, and then tying the trailing end of the twisted 105 yarn on one bobbin to the leading end of the twisted yarn on another bobbin and winding the twisted or ply yarn from the several bobbins in a continuous length onto a receiver. The term spinning as herein 110 used is intended to make clear that the invention may be employed in connection with 115 yarn spun direct from the roving or sliver, but does not restrict the invention in this respect, as manifestly the invention may be advantageously employed in connection with a twister frame, where two or more of the previously spun yarns are twisted together into ply yarn and wound upon a bobbin. In this case the twisted yarn on a series of 120 bobbins will be transferred to the carrier from the twister spindles and the other steps of the method be followed substantially as hereinbefore described with respect to the spun yarn.

The term "yarn" is herein used in its broad sense to include any usual filament or thread and is to be understood in this sense throughout the specification and claims.

What is claimed is:

1. The process of winding yarn from a series of bobbins in one continuous length 130

4. upon a single receiver, which consists in spinning or twisting the yarn upon a series of bobbins with the trailing end exposed, transferring the series of full bobbins to a flexible carrier having bobbin holders disposed to support the bobbins in parallel relation, tying the trailing end of the yarn of one bobbin to the leading end of the yarn on another bobbin successively throughout the series, transferring the flexible carrier to a winding machine constructed to support the carriers so that the ends of the series of bobbins extend in a radial direction towards the winding point, then winding the yarn successively from the bobbins to a single receiver in one continuous length.

5. The process of winding yarn from a series of bobbins in one continuous length upon a single receiver, which consists in 20 winding the yarn upon a series of bobbins with the trailing end exposed, transferring the series of full bobbins to a carrier having bobbin holders disposed to hold the bobbins in parallel relation, tying the trailing end 25 of the yarn of one bobbin to the leading end of the yarn on another bobbin successively throughout the series, transferring the carrier to a winding machine constructed to tilt the bobbins so that the ends of the 30 series of bobbins extend radially toward the winding point, then winding the yarn successively from the bobbins to a single receiver in one continuous length.

6. The process of winding yarn from a 35 series of bobbins in one continuous length upon a single receiver, which consists in winding the yarn upon a series of bobbins with the trailing end exposed, transferring the series of full bobbins to a carrier having 40 bobbin holders disposed to support the bobbins so that their upper ends lie in the same plane, tying the trailing end of the yarn of one bobbin to the leading end of the yarn on another bobbin successively 45 throughout the series, transferring the carrier to a winding machine constructed to support the carrier so that the ends of the series of bobbins extend toward and lie the same distance from the winding point, then winding 50 the yarn successively from the bobbins to a single receiver in one continuous length.

7. A carrier for a series of bobbins, comprising a flexible strip, a series of bobbin supports secured to the flexible strip, and means for supporting the flexible strip to receive full bobbins as they are doffed at the spinning machine for transference of the series to yarn winding position with 60 the flexible strip curved to permit the yarn being drawn from the ends of the bobbins.

8. A carrier for a series of bobbins, comprising a flexible metal strip having a series of bobbin supports secured thereto and constructed to be supported in a straight posi-

tion while the bobbins are applied and in a curved position while the yarn is unwound, and means for supporting the flexible metal strip in a curved position so that the axes of the bobbins extend toward a common point.

9. A carrier for a series of bobbins, comprising a flexible strip having a series of bobbin supports secured thereto and constructed to be supported in a straight position while the bobbins are applied and in a curved position while the yarn is unwound, and means for supporting the flexible strip in a curved position so that the ends of the series of bobbins extend toward and lie the same distance from the winding point.

10. A carrier for a series of bobbins, comprising a narrow and normally straight flexible strip having a series of bobbin supporting spindles secured thereto so that their ends normally lie in the same plane, in combination with a support for detachably holding the flexible strip in curved position with the end portion of the spindles directed to a common point that the yarn may be withdrawn from the ends of bobbins on the spindles in a continuous length.

11. A carrier for a series of bobbins, comprising a flexible strip having a row of bobbin supporting spindles secured thereto so that their ends normally lie in the same plane, in combination with a yarn winding machine having a curved support for detachably holding the flexible strip in curved position with the ends of the bobbin holding spindles directed to a common point that the yarn on the bobbins may be connected and successively withdrawn from the series of bobbins and wound in single length upon a 100 yarn receiver.

12. A carrier for a series of bobbins, comprising a normally straight flexible strip having a series of spindles normally supported in the same plane for receiving a series of bobbins having yarn spun or wound thereon, in combination with a yarn winding machine having a curved strip support for holding the flexible strip in curved position with the ends of the spindles and bobbins thereon directed to a common point that the trailing end of the yarn on one bobbin may be connected to the leading ends of 110 yarn on adjacent bobbins and withdrawn from the ends of the bobbins in succession 115 in a single length, and a receiver for winding the yarn.

13. A carrier for a series of bobbins, comprising a flexible strip having a series of bobbin supporting spindles secured thereto and adapted to be held in straight position to receive bobbins having yarn wound thereon and in a curved position with the ends of the spindles directed to a common point to have the yarn withdrawn endwise 120 of the spindles.

11. A carrier for a series of bobbins, comprising a flexible metal strip, and a series of bobbin holding spindles welded thereto to permit the flexible metal strip to be supported in a straight position to receive bobbins with yarn wound thereon and in a curved position to permit the yarn to be withdrawn endwise of the spindles in succession.
- 10 12. A carrier for a series of bobbins, comprising a flexible metal strip, a series of bobbin holding spindles secured to the flexible strip to permit the strip to be supported in a straight position to receive bobbins with yarn wound thereon and in a curved position to permit the yarn to be withdrawn endwise of the spindles in succession, and
- 5 each spindle having a head portion spot welded to the flexible metal strip.
13. A carrier for a series of bobbins, comprising a flexible strip having a series of bobbin holding spindles and adapted to be supported in either a straight or curved position, in combination with a winding machine having a yarn receiver, means for winding yarn upon the receiver, a curved support for the flexible strip, a yarn guide, and means for detachably positioning the flexible strip on the curved support with the spindles directed towards the yarn guide.
- 20 25 30
- In testimony whereof, I have signed my name to this specification.

DAVID S. SEAMAN.
